LOOM FOR WEAVING WIRE.

No. 288,468.

Patented Nov. 13, 1883.

UNITED STATES PATENT OFFICE.

JOHN McMURRAY, OF BROOKLYN, NEW YORK.

LOOM FOR WEAVING WIRE.

SPECIFICATION forming part of Letters Patent No. 288,468, dated November 13, 1883.

Application filed July 5, 1881. (No model.)

To all whom it may concern:

Be it known that I, JOHN McMURRAY, of Brooklyn, Kings county, and State of New York, have invented certain new and useful 5 Improvements in Looms for Weaving Wire, of which the following is a specification.

My improvements are especially designed for use in looms for weaving wire-cloth, and will be here described as employed in such a 10 loom. Some of them will, however, be found useful in other looms.

My invention consists in various novel features of construction and combinations of parts, hereinafter described, and set forth in the 15 claims.

In the accompanying drawings, Figure 1 is a front view of a loom embodying my improvements, the operator's platform and certain parts being removed. Fig. 2 is a side view of 20 the same, certain parts of the loom being broken away to more clearly illustrate my invention. Fig. 3 is a plan thereof. Fig. 4 is a horizontal section, on a larger scale, of a portion of the shuttle-operating mechanism. Fig. 25 5 is a longitudinal vertical section of the same portion of said mechanism. Fig. 6 is a transverse section of the same portion of said mechanism, taken on the plane of the dotted line x x , Fig. 4, the pins H^6 being in elevation. Fig. 7 is a sectional plan of the shuttle. Fig. 30 8 is a longitudinal section of the shuttle. Fig. 9 is a side view of a part of the let-off mechanism, and Fig. 10 is a sectional plan of the same part of the let-off mechanism.

Similar letters of reference designate corresponding parts in all the figures.

The frame of the loom consists, essentially, of side pieces, A , and stretchers or cross-pieces A' .

I will begin with a description of the warp-beam and the let-off mechanism.

B designates the warp-beam. It is mounted in bearings in the rear portion of the side pieces, A , of the frame A A' , and is provided with a number of flanges, B' , for separating certain portions of the warp-wires from other portions, and thereby lessening their liability to become deranged or entangled. One end is furnished with a worm-wheel, B^2 , which gears into a worm, B^3 , on an upright shaft, B^4 . At 45 the lower end the shaft B^4 is provided with a bevel-gear wheel, B^5 , which engages with a

bevel-gear wheel, B^6 , on a horizontally-arranged shaft, B^7 , mounted in bearings in the side pieces, A , of the frame A A' . To the shaft B^7 are rigidly affixed two wheels, B^8 , 55 (see particularly Figs. 2, 9, and 10,) and loosely mounted on said shaft are levers B^9 , which are made in the form of frames embracing the said wheels within them.

B^{10} designates blocks, which respectively embrace a portion of the periphery and rims of the wheels B^8 , and are connected by chains B^{11} to the upper ends of the levers B^9 . Pivoted to these blocks B^{10} are levers B^{12} , having at their inner ends arc-shaped faces eccentric to their pivots, and bearing against the peripheries of the wheels B^8 . When the outer ends of these levers are raised, their inner ends, in conjunction with the blocks B^{10} , clamp the rims of the wheels B^8 , so that they will 70 serve to impart motion thereto when properly operated. The outer ends of these levers B^{12} are connected by rods B^{13} with the upper ends of the levers B^9 ; hence when the upper ends of these levers B^9 are moved backward, they 75 serve, through the rods B^{13} , to effect the release of the wheels B^8 , and when said ends of the levers B^9 are moved forward, they effect the clamping of the levers B^{12} and blocks B^{10} on the wheels, and then on a further movement 80 they effect the movement of the said wheels B^8 .

The lower ends of the levers B^9 are connected by rods B^{14} with the treadles C , whereby the heddles C' and C'' are operated. The wheels B^8 are therefore moved forward each time the 85 treadles to which they are respectively connected are depressed, and are released and allowed to remain stationary each time the treadles rise. In this way the treadles serve to control the let-off of the warp-wires. 90

The rods B^{14} are connected to the levers B^9 by blocks, which are adapted to be slid, through the agency of screws B^{15} , longitudinally along the lower ends of the said levers, (see particularly Figs. 2, 9, and 10;) hence their points of connection with the said levers may be varied, so as to impart more or less motion to the levers and a greater or less let-off of the warp-wires. In order that the let-off of the warp-wires may be decreased for any purpose—as, 100 for instance, to tighten the warp-wires—I connect one of the blocks B^{10} by a chain, B^{16} ,

with an arm extending from a rock-shaft, B¹⁷, which is provided with another arm that is connected by a rod, B¹⁸, with a lever, B¹⁹, extending to the front of the loom, where it may be reached by the operator.

D designates a platform where the operator stands, and from which he can reach the lever B¹⁹. In lieu of this platform, the loom may be sunken, so that the floor of the room in which it is located will occupy the same relative position to it as this platform. By depressing the forward end of the lever and engaging it with a catch, B²⁰, on the frame A A', the said block B¹⁰ may be raised, so that it and its lever B¹² cannot clamp the corresponding wheel, B⁸, whereupon the let-off mechanism will operate more slowly, and any slack that has occurred may be taken up. By thus varying the speed of the let-off from time to time, I change the distance from the breast-beam at which the reed of the lay E beats up, and as the lay travels through an arc I thus vary the point at which its dents operate on the filling in beating up. This is advantageous, as the reed will then last longer than if its dents operated always at the same point.

The heddles C' and C² are connected at their upper ends by straps, which pass over and are suspended from pulleys C³, and at their lower ends they are each connected to one of two levers, C⁴ C⁵, which are fulcrumed to the side pieces, A, of the frame A A', and are connected by rods C⁶ C⁷ to the treadles C. The treadles C are operated by cams C⁸ C⁹, each cam serving to depress one treadle and raise the other, owing to the connection of the two heddles by the aforesaid straps.

At their forward ends the treadles C have affixed to them upright rods C¹¹, which extend up through the operator's platform D. By depressing either of these rods with his foot, the operator can, when starting the work, actuate the treadles, and through them so adjust the heddles as to open the shed and keep it open as long as necessary for any purpose. The operator by pressing with his foot on either of the rods C¹¹ can operate the treadle connected with the rod quicker than it would be operated by the cam C⁸ or C⁹. Just as either cam is about to act on its treadle, the operator can by the proper rod C¹¹ depress that treadle quickly and release it to permit it to be moved by the cam, and thereby he obtains an additional movement of the treadle.

The lay E is supported by swords mounted on a shaft, E', supported in bearings *a* in the side pieces, A, of the frame A A', and vibrates back and forth in performing its work. The mechanism by which it is operated will be described hereinafter. It is provided with a shuttle-race, E², as usual, which is open on the front of the lay, the swords of which are cut away, as shown in Fig. 2, to allow of the passage of the shuttle.

I will now proceed with detailed description of the shuttle and its operating mechanism, as they come next in order of operation.

G designates the shuttle. It consists of a frame, G, having bifurcate end pieces, G', each provided with a transverse tongue or bar, G². 70

G³ designates the bobbin, which is made in the form of a spool, fitted loosely on a stationary stud, G⁴.

G⁵ designates a metallic spring, which is hinged at one end to the frame G, bears on 75 the top of the bobbin, and has its free end slipped under a hasp, G⁶, on the frame G. By disengaging its free end from the hasp G⁶ the bobbin may be withdrawn.

G⁷ designates a spring fastened at one end to 80 the frame G, and bearing near the other end against the bobbin, so as to constitute a brake for it. It may be faced with leather or other material where it bears against the bobbin. This shuttle travels along the race E² of the 85 lay E to and from shuttle boxes or supports H, affixed to and extending laterally from the side pieces, A, of the frame A A'. In these shuttle boxes or supports H are shuttle-carriers H', which slide lengthwise thereof, and each of 90 which in turn impels the shuttle to the center of the race E² of the lay E and delivers it to the other, whereby it is then carried the remainder of its stroke or pick. These shuttle-carriers H' derive motion from levers or picker-staffs H², which have bifurcate upper ends 95 that embrace cross-pins *b*, with which the said shuttle-carriers are provided near their outer ends. The picker-staffs H² are fulcrumed to lateral extensions A² from the side pieces, A, 100 of the frame A A', and they have the requisite motion imparted to them by cams H³ on a shaft, H⁴, acting on bowls on their lower ends.

The shuttle-carriers H' consist, essentially, of cases H', containing pairs of pincher-like levers H⁴, which at their forward or inner ends lie within and are sheathed by the cases H', and are provided with hooks for grasping the tongues or bars G² of the shuttle G, but at their rear ends protrude through the sides of 110 the cases H'. Near their rear ends these levers have inclined faces, to enable them to be operated upon by vertically-moving studs or pins H⁵, presently to be described, and they are at the said ends held apart by springs H⁶. 115 when not otherwise actuated, so that their forward ends will then be impelled toward each other. The two pincher-like levers H⁴ of each pair are both adapted to swing on a common fulcrum for taking and releasing the 120 shuttle.

The end pieces, G', of the shuttle are adapted to enter openings in the ends of the cases H' of the shuttle-carriers, so that the hooks of the pincher-like levers H⁴ may engage with 125 their tongues or bars G². Supposing one of the end pieces, G', of the shuttle to be thus engaged with one of the shuttle-carriers H', the shuttle is then carried to the center of the race E² of the lay E when the latter arrives at the 130 proper position, and the other shuttle-carrier H' comes forward to receive it. The studs or pins H⁵ belonging to the shuttle-carrier which has thus far carried the shuttle are operated

so that they will obtrude themselves in position to open the forward ends of the pincher-like levers H^4 of that shuttle-carrier when the said shuttle-carrier arrives at the end of its stroke; hence the shuttle is released from that shuttle-carrier. It is simultaneously delivered to the other shuttle-carrier, and the hooks on the forward ends of the pincher-like levers of the latter then engage with the tongue or bar G^2 of the adjacent end piece, G' , of the shuttle, and the latter is drawn by the last-named shuttle-carrier through the remainder of its stroke or pick. This operation of the shuttle is reversed at the next stroke or pick of the shuttle, and thus the shuttle-carriers continue to operate.

H' designates levers fulcrumed to the shuttle boxes or supports H , and having bifurcate lower ends, which, when the shuttle-carriers H' are at the outer end of their strokes, may be turned down to grasp the protruding rear ends of the pincher-like levers H^4 , and cause their forward ends to release the shuttle. Springs H^8 , applied to the upper ends of these levers H^7 , hold the lower ends of the said levers out of engagement with the said pincher-like levers H^4 , except when they are desired to operate. When this occurs, it is only necessary to pull cords H^9 , which are fastened to the upper ends of the said levers H^7 , to accomplish the aforesaid result.

The studs or pins H^5 form extensions of rods H^{10} , which are connected to levers H^{11} , that are fulcrumed to the front portion of the side piece, A , of the frame $A A'$. The levers H^{11} are operated at proper times by cams H^{12} , arranged on the shaft C^{10} .

The lay E has rigidly connected with it levers E^3 , which extend forward and rearward from the shaft E' , and which at their rear ends bear upon cams E^4 on the shaft H^{14} , and at their forward ends carry a weight, E^5 , which is shown as made in the form of a roller, and can be attached to the said arms at different distances from the fulcrum of the lay-swords. The levers E^3 are supported or held in stirrups s , which are fixed upon the shaft E' , as seen clearly in Fig. 1.

The lower ends of the lay-swords are extended below the shaft E' and are rearwardly bent, and they are provided at their lower ends and below the shaft E' with bowls, which bear against cams E^6 on the shaft H^4 . The lay is swung backward by the action of the cams E^6 on its swords, and at the end of its backward stroke is released by these cams. It is then started on its beat or forward stroke by the action of the cams E^4 on the levers E^3 ; but as soon as it is carried sufficiently far forward these cams release it, and thereupon the weight E^5 carries it forward to the completion of its stroke and makes its reed beat up the weft-wire last laid in the shed by the shuttle with a powerful blow. This is an important feature of the loom, especially for weaving wire-cloth.

It will be seen that inasmuch as the lay is at certain times freed from the cams which op-

erate it, I can stop the loom and work the lay by hand for any purpose—as, for instance, when a wire breaks.

I have before described how the distance from the breast-beam at which the lay beats up may be varied by operating the lever B^{19} , and it is evident that this could not be done if the lay were operated by mechanism which caused it to beat up at an invariable distance from the breast-beam. When the lay moves forward to beat up by the influence of gravity, it will continue to move until the dents of its reed beat the last weft-wire up to the cloth-making point, at whatever position that may be. In weaving wire-cloth it is more difficult to beat up properly than in weaving textile fabrics, because it requires much more power to beat the weft-wire up to its proper position, or to force it up between the warp-wires. The beating up can never be done effectively by pressing or forcing the lay forward, and I have found that it must be performed by a blow. Another advantage of beating up by a blow is that the lay will rebound after first striking and strike a second time on the weft-wire, thus subjecting each of the weft-wires to two beats instead of one.

I do not here claim the take-up mechanism shown, and a very brief description thereof will be all that is required.

I designates the breast-beam, and J the take-up beam. The take-up beam carries ratchet-wheels J' , which are operated directly by levers J^2 , carrying-pawls J^3 . The levers J^2 are provided with bowls J^6 and weights J^7 , and are actuated by cams J^4 on a shaft, J^5 .

The shaft H^{14} , as here shown, constitutes the driving-shaft of the machine, and may have motion transmitted to it through the agency of a gear-wheel, K , with which it is provided. Motion is imparted by this shaft to the shafts C^{10} and J^5 by gear-wheels L , suitably proportioned to each other to attain the desired relative movements of the parts which are operated from said shafts.

M designates a shipper-bar for adjusting a belt or clutch, to control the driving of the loom from a counter-shaft or other source of power.

What I claim as my invention, and desire to secure by Letters Patent, is—

1. The combination, with a warp-beam and an upright shaft, and mechanism for transmitting motion to the warp-beam from said shaft, of the wheels B^2 B^6 , the horizontal shaft B' , the wheels B^8 , the blocks B^{10} , embracing the rims of said wheels B^8 , the levers B^{12} , pivoted in said blocks, and having their inner ends bearing against the wheels B^8 , and means for actuating said blocks and said levers, substantially as specified.

2. The combination, with a warp-beam, a gear-wheel, B^2 , an upright shaft, B^4 , and a worm, B^3 , of the wheels B^2 B^6 , the horizontal shaft B' , the wheels B^8 , the blocks B^{10} , embracing the rims of the wheels B^8 , the levers B^{12} , pivoted in said blocks, and having their inner ends bearing on said wheels B^8 , and means

for actuating said blocks and levers, substantially as specified.

3. The combination, with a warp-beam, an upright shaft, and mechanism for transmitting motion to the warp-beam from said shaft, of the wheels B⁵ B⁶, the horizontal shaft B⁷, the wheels B⁸, the blocks B¹⁰, embracing the rims of said wheels B⁸, the levers B¹², pivoted in said blocks, and having their inner ends bearing upon said wheels B⁸, the levers B⁹, loosely mounted on the shaft B⁷, the rods B¹³, and means for imparting motion to the levers B⁹, substantially as specified.

4. The combination, with a warp-beam and an upright shaft, and mechanism for transmitting motion to the warp-beam from said shaft, of the wheels B⁵ B⁶, the horizontal shaft B⁷, the wheels B⁸, the blocks B¹⁰, the levers B¹², the levers B⁹, the rods B¹³, the treadles C, and the rods B¹⁴, connecting the levers B⁹ with said treadles, substantially as specified.

5. The combination, with a warp-beam, an upright shaft, and mechanism for transmitting motion to the warp-beam from said shaft, of the wheels B⁵ B⁶, the horizontal shaft B⁷, the wheels B⁸, the blocks B¹⁰, the levers B¹², the levers B⁹, the rods B¹³, the rods B¹⁴, the treadles C, the blocks connecting the rods B¹⁴ with the levers B⁹, and the screws B¹⁵, substantially as specified.

6. The combination, with a warp-beam, an upright shaft, and mechanism for imparting motion to the warp-beam from said shaft, of the wheels B⁵ B⁶, the horizontal shaft B⁷, the wheels B⁸, the blocks B¹⁰, the levers B¹², the levers B⁹, the chains B¹¹, the rods B¹³, means for actuating the levers B⁹, the chain B¹⁶, the rock-shaft B¹⁷ and its arms, the rod B¹⁸, and the lever B¹⁹, substantially as specified.

7. The combination, with a warp-beam, an upright shaft, and mechanism for transmitting motion to the warp-beam from said shaft, of the wheels B⁵ B⁶, the horizontal shaft B⁷, the wheels B⁸, the blocks B¹⁰, the levers B¹², the levers B⁹, the chains B¹¹, the rods B¹³, means for actuating the levers B⁹, the chain B¹⁶, the rock-shaft B¹⁷ and its arms, the rod B¹⁸, the lever B¹⁹, and the catch B²⁰, substantially as specified.

8. The combination, with a warp-beam, an upright shaft, and mechanism for transmitting motion to the warp-beam from said shaft, of the wheels B⁵ B⁶, the horizontal shaft B⁷, the wheels B⁸, the blocks B¹⁰, the levers B¹², the levers B⁹, the chains B¹¹, the rods B¹³, the rods B¹⁴, the treadles C, the rods C¹¹, and the operator's platform D, substantially as specified.

9. The combination, with the lay E, having the race E², of the shuttle G, with its end pieces, G', and tongues or bars G², the pincher-like levers H⁴, mounted on a common fulcrum, and both adapted to be swung to take and release the shuttle, the shuttle-carriers H', inclosing said levers, and mechanism for operating said shuttle-carriers and said levers, substantially as specified.

10. The combination, with the lay E, having the race E², of the shuttle G, with its end pieces, G', and tongues or bars G², the shuttle-carriers H', the pincher-like levers H⁴, inclosed by said carriers, and having at their rear ends inclines which project through the carriers, the springs H⁶, the studs or pins H⁵, between which the carriers pass, and which are adapted to act on the inclines of said levers H⁴ to open them, and mechanism for actuating said shuttle-carriers and said studs or pins, substantially as specified.

11. The combination, with the lay E, having the race E², of the shuttle G, with the end pieces, G', and tongues or bars G², the shuttle-carriers H', the pincher-like levers H⁴, inclosed in said carriers, and provided at their rear ends with inclines projecting through the carriers, the springs H⁶, the picker-staffs H², the cams H³, the studs or pins H⁵, between which the shuttle-carriers pass, and the rods H¹⁰, levers H¹¹, and cams H¹², for raising said studs or pins into a position to act upon the levers H⁴, substantially as specified.

12. The combination of the shuttle-carriers H', and mechanism for operating them, with the pincher-like levers H⁴, the springs H⁶, and the levers H¹, substantially as specified.

13. The combination, with the lay-shaft E' and the lay E, fulcrumed on and extending upward from said shaft, of the levers E³, extending forward and rearward from said lay-shaft, the shaft H¹⁴ and means for rotating it, the cams E⁴, for acting on the rear portions of said levers for starting the lay forward, and the weight E⁵, applied to the forward ends of said levers for completing the forward movement of the lay, whereby the reed is made to strike with a blow upon the weft-wire, and provision is afforded for varying the distance from the breast-beam at which the lay beats up, substantially as specified.

14. The combination, with the lay-shaft E' and the lay E, fulcrumed on and extending upward from said shaft, of the levers E³, extending forward and rearward from said lay-shaft, the shaft H¹⁴ and means for rotating it, the cams E⁴, for acting on the rear portions of said levers, to start the lay forward, and the weight E⁵, applied to the forward ends of said levers for completing the forward movement of the lay, whereby the lay is made to strike with a blow upon the weft-wire, and provision is afforded for varying the distance from the breast-beam at which the lay beats up, and the cams E⁶, for acting on the lay-swords below the fulcrum-shaft E', to move the lay back after beating up, substantially as specified.

JOHN McMURRAY.
